CLAIM

The ornamental design for a quick connector, as shown and described.

DESCRIPTION

FIG. 1 is a first perspective view of a quick connector showing our new design;

FIG. 2 is a second perspective view thereof;

FIG. 3 is a third perspective view thereof;

FIG. 4 is a fourth perspective view thereof;

FIG. 5 is a fifth perspective view thereof.

FIG. 6 is a front elevational view thereof;

FIG. 7 is a rear elevational view thereof;

FIG. 8 is a top plan view thereof;

FIG. 9 is a bottom plan view thereof;

(Continued)

FIG. 10 is a left side view thereof; and,
FIG. 11 is a right side view thereof.

1 Claim, 11 Drawing Sheets
